SAFETY RAZOR

Filed Nov. 18, 1929

Inventor:
ARTHUR A. GROTHE

By *Ernest J. O'Byrne*

UNITED STATES PATENT OFFICE

ARTHUR A. GROTHE, OF OAK PARK, ILLINOIS, ASSIGNOR TO WILLIAM J. CAMERON, OF CHICAGO, ILLINOIS

SAFETY RAZOR

Application filed November 18, 1929. Serial No. 407,830.

My present invention relates to safety razors, and it has more particular reference to the manner of attaching the blade-carrying head to the handle and for compressing 5 the blade between the parts of the head.

In safety razors of a well-known type the thin double edged blade is maintained in position between the members of two-part head by screwing the removable handle upon the 10 threaded stud that projects from one of the members of the head. While this is an effective manner of assembly it is subject to the objection that time is always required to properly interengage the threads of the handle socket and the threaded stud and additional time is required to rotate the handle 15 upon the proper extent to securely clamp the thin blade between the parts of the head. A further objection to this type of structure is the 20 fact that the user must rely solely upon his judgement as to the proper amount of tension to be given the flexed blade in order that effective shaving operation may be performed.

With my present construction I have successfully 25 eliminated the above mentioned inherent objections, and I have provided a safety razor structure wherein the parts of the head and the blade may be readily assembled with the handle, and after this assembly the tension upon the flexed blade may 30 be adjusted to predetermined positions for operation. The adjustment last-mentioned, while it may be slight, nevertheless, it is essential for persons using the razor and with 35 my improvement may be accomplished to a nicety.

My invention has numerous objects in view, among which are the ease and readiness with 40 which the parts of the razor may be assembled and adjusted for operation, the compactness of the parts so that they will not occupy a large space or become cumbersome when not in use; the dependability with 45 which the device may be used or manipulated, and the novel manner in which the parts are assembled which permit the razor to be manufactured and sold for a reasonable price.

I prefer to accomplish the before-mentioned and other objects, and to carry out my 50 invention in substantially the manner here-

inafter fully described and as more particularly pointed out in the claims, reference being herein made to the accompanying drawing that forms a part of this specification.

55 In the drawing:

Fig. 1 is a view in side elevation of my invention applied to a safety razor and showing the parts in separated positions preparatory to assembly.

Figure 2 is a vertical fragmentary view of 60 a portion of my invention the view being a section taken on line 2-2 of Figure 3, and drawn to an enlarged scale.

Figure 3 is a transverse section on line 3-3 65 of Figure 2, drawn to a smaller scale than said figure and looking in the direction of the arrows.

Figure 4 is a fragmentary view showing in detail the assembly of the head with the 70 handle and illustrating the initial positions of the parts and just prior to the clamping of the parts.

Figure 5 is a similar view showing the parts in the first clamping position.

Figure 6 is a similar view showing the 75 second clamping position.

Figure 7 is a layout pattern of the lower portion of the sleeve on the guard plate.

The drawing is to be understood as more or 80 less schematic for the purpose of illustrating a typical or preferred form in which the structure may be made, and in said drawing the same reference characters have been employed to designate like parts wherever they appear throughout the several views.

In the drawing, 10 represents the handle to which the blade-carrying head is detachably secured, and the manner of mounting of the head on said handle is such that there may be a slight adjustment of the guard and 90 clamping members of the head in order to secure different tensions upon the blade and change the relation of the cutting edge of the blade with respect to said guard. The guard which forms a coating portion of the head consists of a rectangular plate 11 of concavo convex cross-section that is provided with a central stud 12 and a pair of guide pins 13 arranged one on each side of the stud 95 in longitudinal alinement with each other.

The end portion of the stud is reduced in diameter to provide a neck 14 and beyond the latter there is an enlargement in the form of a rectangular shaped cross-piece 5, so that a locking member or key is provided upon the end of the stud.

The clamping member consists of a concavo-convex rectangular plate 16 having therein a central aperture 17 that is between two spaced apertures 18 which receive and coact with the stud and guide pins of the clamping plate 11. The adjacent or opposing faces of the clamping plate and guard plate substantially correspond in curvature, and when the thin double-edged blade 19 is interposed between these members it is flexed transversely as the members are drawn together.

Surrounding the central aperture 17 of the guard member there is a tubular sleeve 20 that projects from the concave face of said member to a point slightly beyond the key on the stud 12 when the guard and clamp are assembled. The lower or outer end of the sleeve is of irregular shape as shown so as to provide a pair of diametrically opposite tongues or stops 21 that extend longitudinally from the end edge of the sleeve in the manner shown, and intermediate these tongues or stops the lower or end edge of the sleeve is somewhat undulated so as to provide a plurality of distinct niches or recesses 22, 23, and 24, each of which is located a different distance from the guard plate 16. In other words these niches or recesses are disposed spirally or in a plane inclined or oblique to a plane at a right-angle to the axis of the sleeve or the plane of what was the adjacent end edge of the sleeve. For convenience in understanding, a diagrammatic flat lay-out or pattern of this portion of the structure is illustrated in Figure 7, which shows its cam-like formation.

The handle is preferably a hollow cylindrical casing 10, with its upper end closed by a plug 25, and a conical shaped protecting cap 26, is screwed thereon that has its upper end truncated and provided with an opening 27, through which the centrally projecting elements of the guard and clamping members enter the end of the handle for co-operation with the handle parts that are adapted to interlock therewith. These interlocking parts are enclosed within the cap 26, and are preferably carried by the plug 25 or end of the handle.

There is preferably a post 28 that has its reduced and knurled lower end 29 imbedded in the material of which the handle or end plug are formed, and near its outer end the post is trans-axially bored to receive a transverse stop-pin 30 the ends of which project beyond the sides. As will be seen the length of the stop-pin is not less than the outside diameter of the sleeve 20 that depends from

the guard plate, so that the tongues 21 of said sleeve may be engaged with opposite ends of said stop-pin when the sleeve is inserted into the cap and over the post. In this position the ends of the stop-pin will be positioned in the initial niche or recess 22 in the lower edge portion of said sleeve.

A cage or box 31 surrounds the post between the latter and the sleeve 20, and it is of cylindrical cross-section with its lower end closed by a cup-shaped head 32 that is screwed thereon and has a central opening through which the post passes. The opposite or outer end of the box is closed by an integral wall 33 having a diametrical slot 34 that has extensions 35 that extend down into the side wall of the box so that a suitable socket is provided into which the neck and key 14 and 15 may be inserted and locked, the latter being accomplished by a relative rotative movement between the respective parts which will position the key head back of the end wall 33, as shown in Figure 2, and indicated in dotted lines in Figure 3. The side wall of the box is provided with alining holes 36 having diameters greater than the diameter of the stop pin 30 that passes therethrough so that there may be a slight independent relative movement in a longitudinal direction between the pin and box.

A coiled expansion spring 37 surrounds the post between the stop pin and the cup-shaped closure head that is placed in the box prior to the screwing of the head upon the box. As will be seen, one end of the spring bears against the stop-pin and its opposite end is seated against the closure head so as to urge the box downwardly towards the handle and yieldably maintain the stop-pin in the upper portions of the holes 36 as illustrated in Figure 2.

The operation or assembly of the head and handle is as follows:—The flexible blade is placed between the clamping member and the guard member, in which position the stud 12 will be inside the sleeve 20, and these latter parts are then inserted in the hole 27 in the handle cap and moved inwardly and slightly rotated until the key 15 passes through the slot 34 into the interior of the box. Meanwhile the end of stop-pin 30 will be engaged with the tongues 21 in the initial undulation or recess 22 in the end edge of the sleeve. A relative rotative movement between the head and the handle members will position the key bar 15 under or back of the end wall 33 of the box and it will be locked against longitudinal movement. A further rotative movement of the parts will cause the undulated edge of the sleeve 20 to push the stop-pin 30 downwardly against the spring 37 while the pin will move toward the opposite segment of the holes 36 in the sides of the box until the niche or recess 23 is entered by the ends of the pin. These movements of

the parts will have caused the flexing of the blade between the guard and clamping members due to the drawing of these members towards each other and the niche will maintain the parts against accidental movement in a rotative direction.

Should it be desired to flex the blade to a further extent the head or handle may be rotated until the pin seats in the last niche 24, 10 and against the tongues, in which position the blade will be flexed to its full limits between the guard and clamping members and is in position for use the same as when the pin is in the niche 23. A reverse rotative 15 movement between the head and handle will release the guard and clamping members of the head and the latter may be withdrawn from the handle and the members may be separated to remove the blade.

20 What I claim is:—

A safety razor comprising a blade carrying head and a handle therefor, said head

comprising a guard member and clamping member for securing a blade between the guard and clamping member, a stub tube extending down from said guard, a stud on the clamp member telescoped in said tube, a hollow extension yieldingly mounted on the adjacent end of the handle having a key-way in its outer end and telescoped by said tube, a key on said stud that interlocks with said key-way, a stationary post at the end of the handle on which said hollow extension is mounted and which extends up into said extension, and lateral members on said post that project through said extension, to engage the lower edge of said stub tube, said stub tube having a graduated notched lower edge coacting with said lateral members for pre-determining the adjustable flexing of the blade.

Signed at Chicago, Cook County, Illinois, 85
this 22nd day of August, 1929.

ARTHUR A. GROTHE.
